N. P. WILCOX

FRUIT JAR OR SIMILAR ARTICLE

Filed Sept. 12, 1924

Inventor:

Neva P. Wilcox,
By Dyerforth, L. C. Chitton & Miles.
Attest:

UNITED STATES PATENT OFFICE.

NEVA P. WILCOX, OF WEST NEWTON, MASSACHUSETTS.

DESIGN FOR A FRUIT JAR OR SIMILAR ARTICLE.

Application filed September 12, 1924. Serial No. 10,760. Term of patent 7 years.

To all whom it may concern:

Be it known that I, NEVA P. WILCOX, a citizen of the United States, residing in the city of West Newton, county of Middlesex, and State of Massachusetts, have invented a new, original, and ornamental Design for a Fruit Jar or Similar Article, of which the following is a specification, reference being had to the accompanying drawing, forming part thereof.

The figure is a perspective view of a fruit jar or similar article.

I claim:

The ornamental design for a fruit jar or similar article as shown.

NEVA P. WILCOX.
